UNITED STATES PATENT OFFICE.

MATTHEW S. CUMNER, OF NEW YORK, N. Y.

VISE.

1,406,981.

Specification of Letters Patent.

Patented Feb. 21, 1922.

Application filed July 21, 1919. Serial No. 312,407.

To all whom it may concern:

Be it known that I, MATTHEW S. CUMNER, a citizen of the United States of America, and resident of the city, county, and State 5 of New York, have invented certain new and useful Improvements in Vises, of which the following is a specification, reference being had to the accompanying drawings, forming a part thereof.

10 My present invention relates to clamps or vises and is in the nature of an improvement on similar devices previously patented by me.

A special object of the present invention 15 is to force the movable jaw firmly against the work and to overcome the tendency of this jaw to incline backwardly as it is engaged with the work.

Other objects of the invention are to 20 simplify and strengthen the device.

Briefly the invention comprises a base carrying one of the jaws of the clamp and a movable jaw slidably mounted on said base, said movable jaw having a connecting block loosely mounted therein and having also a wedging connection with the jaw, together with means, such as a screw, engaged with the block for operating the movable jaw.

30 Other features of the invention and details of construction will appear as the specification proceeds.

The accompanying drawings illustrate the invention embodied in one of its practical and preferred forms, but it will be understood that the structure may be modified in certain respects without departure from the true spirit and scope of the invention.

40 In said drawings:

Figure 1 is a top plan view of the device, with the cover plate on the movable jaw shown as partly broken away to expose the connecting block seated in said jaw.

45 Figure 2 is a side elevation of the device.

Figure 3 is a longitudinal central sectional view, taken substantially on the plane of line 3—3 of Figure 1.

50 Figure 4 is a longitudinal sectional view, taken at one side of the central plane and substantially on the line 4—4 of Figure 6.

Figure 5 is a similar sectional view, illustrating the jaws clamped upon a piece of work.

Figure 6 is a transverse sectional view on 55 substantially the plane of line 6—6 of Figure 4.

The base of the device is designated 7 and the same is shown as carrying the integral jaw 8 at one end and as provided 60 with a lug 9 at the opposite end, forming a bearing for the jaw closing screw 10. This bearing may be made as an open bearing, such as indicated, having a removable cap 11, held in place by screws 12.

65 The base further is provided with a track 13 for the movable jaw. 14 designates the movable jaw which is slidably engaged on the track portion of the base and which is formed in the present disclosure with an open top chamber 15 therein, said chamber having a longitudinally extending slot 16 in the bottom thereof registering with a corresponding slot 17 formed in the track portion of the base.

70 At the opposite sides of the slot 16 and near the forward end thereof upwardly inclined shoulders 18 are provided, said shoulders being shown as carried by the hardened metal strips or tracks 19 secured to the movable jaw by screws 20 at the opposite sides of the slot.

75 Engaged within the chamber in the movable jaw is a connecting member in the form of a block 21 having a head portion disposed 85 within the chamber and riding on the tracks 19 and a reduced dependent portion 22 extending down through the registering slots in the movable jaw and base. This dependent extension carries a part engaged beneath 90 a portion of the base, said part being shown as a plate 23, wider than the slot 17, secured to the lower edge of the extension 22 by screws 24 and slidably engaging the under surface of the base.

95 The connecting block is loosely engaged within the chamber and slot in the movable jaw, as indicated particularly in Figures 3, 4 and 6 and therefore may be considered as having a lost motion connection with said 100 jaw. This block furthermore has a wedging connection with the jaw, by means of the in-

clined shoulders 25 at the forward end thereof, which bear upon the inclined shoulders 18 of the jaw.

The movable jaw is actuated by the screw 5 10 previously referred to through the medium of the connecting block 21, said block having in the present disclosure a screw seat 26 to take the screw and the screw being formed with shoulders 27 engaging the opposite faces of the bearing 9-11. This screw passes freely through the opening 28 provided in the rearward wall of the movable jaw. The chamber in which the connecting block is seated is preferably closed 15 by a cover 29, which may be readily removable for purposes of inspection or repair.

From the foregoing it will be apparent that as the screw 10 is turned the connecting block will be carried in one direction or the 20 other and will, through its lost motion connection with the movable jaw, shift said jaw either in the opening or closing direction. As the jaw is shifted in the closing direction the inclined shoulders 25 of the connecting 25 block engage the similarly inclined shoulders 18 of the jaw, as indicated in Figure 5, and riding over said shoulders force the movable jaw firmly downward upon the base and into rigid holding engagement with the 30 work, indicated at 30. Any lost motion between the movable jaw and the trackway on which it rides is thus taken up as the jaw is closed, by forcing the front end of the jaw firmly down on the base. This wedging 35 action is illustrated to an exaggerated degree in Figure 5, which shows the movable jaw as actually tilted slightly downward. In practice this action is hardly perceptible but the effect is evident in the way that the 40 work is gripped as firmly at the top as at the bottom of the jaw. This wedging connection also forms an automatic adjustment to take up the wear of the parts.

The bottom, sides and fixed jaw end of 45 the base 7 are finished surfaces having rectangular relations. Thus the work 30 held between the jaws may be drilled or machined on different sides without being removed from the vise, and holes made or surfaces 50 finished in desired relative positions. This construction makes the vise particularly desirable for drill press work.

What I claim is:

1. In a clamp, a base carrying one jaw 55 of the clamp and provided with a longitudinal slot, a jaw slidably engaged on said base and provided with a slot registering with the slot in the base, a connecting block carried by the movable jaw and having 60 a dependent portion extending through the slots in the jaw and base, said block having a lost-motion connection with the jaw and said block and movable jaw having inclined shoulders engaging as the lost-motion is 65 taken up in the jaw closing movement, and

jaw closing means operating on said connecting block.

2. In a clamp, a base carrying one jaw of the clamp and provided with a longitudinal slot, a jaw slidably engaged on said base and provided with a slot registering with the slot in the base, a connecting block carried by the movable jaw and having a dependent portion extending through the slots in the jaw and base, said block having a lost-motion connection with the jaw and said block and movable jaw having inclined shoulders engaging as the lost-motion is taken up in the jaw closing movement, and a jaw closing screw engaged with said connecting block 80 and operating free of the movable jaw.

3. In a clamp, a base carrying one of the clamp jaws, a cooperating jaw movably mounted on the base and provided with a chamber having an inclined shoulder, a connecting block having a lost-motion engagement in said chamber and provided with an inclined shoulder to engage the inclined shoulder of the movable jaw on the closing movement thereof, and jaw closing means 90 connected with the movable jaw through the medium of said connecting block.

4. In a clamp, a base carrying one of the jaws of the clamp, a jaw member slidably mounted on the base and confined thereto 95 by a part engaged beneath a portion of the base, said movable jaw having a slot therein extending in the direction of the jaw movement, a block loosely seated in said slot, said block and jaw having cooperating inclined shoulders engaging in the jaw closing movement, and a jaw closing device engaged with said block.

5. In a clamp, a base carrying one of the jaws of the clamp and provided with a slot 105 extending in the direction of jaw movement, a movable jaw mounted on the base and provided with a slot in line with the slot in the base, said movable jaw having inclined shoulders at opposite sides of said slot, a 110 connecting block having a dependent portion disposed in the registering slots in the base and jaw and inclined portions over-standing the inclined shoulders of the jaw, and jaw closing means engaged with said 115 connecting block.

6. In a clamp, a base carrying one of the clamp jaws, a movable jaw mounted on said base and provided with a slot therein and with inclined shoulders at opposite sides of said slot, a connecting block having a dependent portion engaged in said slot and provided with a holding portion engaged beneath a portion of the base, said block having inclined shoulders engaging the inclined shoulders of the movable jaw in the jaw closing movement, and a jaw closing device engaged with said block.

7. In a clamp, a base carrying a relatively fixed jaw and provided with a slot extend-

ing in the direction of the jaw closing movement, a movable jaw slidably engaged on the base and provided with a chamber having a slot in the bottom thereof registering with the slot in the base, said chamber having upwardly inclined shoulders at the forward end thereof at opposite sides of the slot and provided with an opening in the rearward wall thereof, a connecting member having a 5 head portion loosely engaged in the chamber and a reduced dependent portion extending down through the slots in the jaw and base and provided at the lower end of said extension with a confining plate for engagement with the under surface of the base, the head portion of said member having inclined shoulders at the forward end thereof engaging the inclined shoulders of the jaw, and a jaw closing screw extending through 10 the opening in the rearward wall of the movable jaw into engagement with the connecting member aforesaid.

8. In a clamp, a base carrying a relatively fixed jaw, a movable jaw slidably mounted 25 on the base and provided with a chamber open at the top and having a slot in the bottom thereof, a connecting block loosely seated in said chamber and provided with a dependent portion extending down through 30 the slot and engaged beneath a portion of the base, said block and jaw having cooperating inclined shoulders engaging in the jaw closing movement, a cover closing the opening in the top of the chamber, and a jaw 35 closing device engaged with said connecting block.

9. In a clamp, a base carrying a relatively fixed jaw, a movable jaw slidably mounted on the base and provided with a chamber 40 having a slot in the bottom thereof, hardened metal tracks secured in said chamber at the opposite sides of said slot and provided with inclined shoulders, a connecting block having a head portion riding on said 45 tracks and inclined shoulders to engage the inclined shoulders of the tracks, said connecting block having a dependent portion extending down through the slot and engaged beneath a portion of the base, and jaw 50 closing means engaged with said block.

10. In a clamp, a base carrying one of the clamp jaws, a cooperating jaw movably mounted on the base and provided with a chamber having a wedging shoulder, a connecting block having a lost-motion engagement in said chamber and provided with a wedging shoulder to engage the wedging shoulder of the movable jaw on the closing movement thereof, and jaw closing means 55 connected with the movable jaw through the medium of said connecting block.

11. In a clamp, a base carrying one of the clamp jaws, a cooperating jaw movably mounted on the base and provided with an 60 inclined shoulder, and jaw closing means

comprising a connecting block having an inclined shoulder arranged to contact with the inclined shoulder of the jaw on the closing movement thereof, and means for moving said block.

12. In a clamp, a base carrying one of the clamp jaws, said base having a finished surface parallel with said jaw and other finished surfaces at right angles to said jaw and to each other, a cooperating jaw movably mounted on the base and provided with an inclined shoulder, and jaw closing means comprising a connecting block having an inclined shoulder arranged to contact with the inclined shoulder of the jaw, and means for moving said block.

13. In a clamp, a base carrying one jaw of the clamp, a movable jaw member slidably mounted on said base, a connecting block carried by the movable jaw member, a jaw closing device engaged with the connecting block, engaging means between said movable jaw member and the connecting block arranged to cause said jaw member to move with the connecting block until its movement is resisted and to cause further movement of the connecting block to lock said jaw member between the connecting block and the base.

14. In a clamp, a base carrying one jaw of the clamp and provided with a longitudinal slot, a movable jaw member slidably mounted on said base and provided with a slot registering with the slot in the base, a connecting block carried by the movable jaw member and having a dependent portion extending through said slots, a member wider than the slot in the base, affixed to said depending portion, a jaw closing device engaged with the connecting block, engaging means between said movable jaw member and the connecting block arranged to cause said jaw member to move longitudinally with the connecting block until its movement is resisted and to cause further longitudinal movement of the connecting block to raise the connecting block and to lock said jaw member between the connecting block and the base.

15. In a clamp, a base carrying one of the clamping jaws, a cooperating jaw member movably mounted on the base, a jaw closing means comprising a connecting block, there being inclined abutting portions between the jaw member and the block arranged to contact to move the jaw longitudinally and to slide to lock said jaws together, and means for moving said block.

16. In a clamp, a base carrying one of the clamping jaws, a cooperating jaw member movably mounted on the base, a jaw closing means comprising a connecting block, there being inclined abutting portions between the jaw member and the block arranged to contact to move the jaw longitudinally and to

slide to lock said jaws together and to force said jaw member downwardly, and means for moving said block.

17. In a clamp, a base carrying one of the clamping jaws, a cooperating jaw movably mounted on the base and provided with an inclined shoulder, a jaw closing means comprising a connecting block having an inclined shoulder arranged to contact with

the inclined shoulder of the jaw member to move said jaw member longitudinally and to slide to exert a downward and forward pressure upon the movable jaw member through said shoulders, and means for moving said block.

In witness whereof, I hereunto set my hand this 18th day of July, 1919.

MATTHEW S. CUMNER.
